(57) **CLAIM**

The ornamental design for an eye bracket for an eye irrigation bottle, as shown and described.

DESCRIPTION

FIG. 1 is a front and left-side perspective view of an eye bracket for an eye irrigation bottle embodying my new design, the dotted lines representing an exemplary canister; FIG. 2 is a front and left-side perspective view of an eye bracket for an eye irrigation bottle embodying my new design;

FIG. 3 is a front elevational view thereof, the rear elevational view being identical;

FIG. 4 is a right-side elevational view thereof;

FIG. 5 is a top plan view thereof; and,

FIG. 6 is a bottom plan view thereof.

The broken line showing of the canister in FIG. 1 and the inside of the cap in FIG. 5 is included for the purpose of illustrating use and environment and forms no part of the claimed design.
